DOLL

Isabel I. Meeker, Philadelphia, Pa.

Application December 17, 1951, Serial No. 17,762

Term of patent 3½ years

(Cl. D34—4)

To all whom it may concern:

Be it known that I, Isabel I. Meeker, a citizen of the United States, residing at Philadelphia, in the county of Philadelphia, and State of Pennsylvania, have invented a new, original, and ornamental Design for a Doll, of which the following is a specification, reference being had to the accompanying drawing, forming a part thereof.

In the drawing:

Fig. 1 is a front elevational view of a doll, showing my new design;

Fig. 2 is a rear elevational view of the same;

Fig. 3 is a side elevational view of the doll; and

Fig. 4 is a top plan view of the same.

I claim:

The ornamental design for a doll, as shown.

ISABEL I. MEEKER.
